(74) Attorney, Agent, or Firm — CANTOR COLBURN LLP

(57) **CLAIM**

The ornamental design for a label, as shown and described.

DESCRIPTION

FIG. 1 is a perspective view of a label, showing our new design;

FIG. 2 is a front view of FIG. 1;

FIG. 3 is a rear view of FIG. 1;

FIG. 4 is a side view of FIG. 1;

FIG. 5 is an opposite side view of FIG. 1;

FIG. 6 is an end view of FIG. 1; and,

FIG. 7 is an opposite end view of FIG. 1.

The broken line portion of the figure drawings is included to show portions of the article that form no part of the claimed design. The dash-dot lines define the bounds of the claimed design and form no part thereof.

1 Claim, 5 Drawing Sheets
